UNITED STATES PATENT OFFICE.

GRAVES R. MAUPIN, OF MOBERLY, MISSOURI, ASSIGNOR, BY MESNE ASSIGNMENTS, TO THE J. FAESSLER MANUFACTURING COMPANY, OF MOBERLY, MISSOURI, A CO-PARTNERSHIP COMPOSED OF JOHN W. FAESSLER, CHRISTINIA FAESSLER, LOUIS E. FAESSLER, AND GRAVES R. MAUPIN.

COMBINATION BOILER TOOL.

Application filed August 16, 1920. Serial No. 404,000.

To all whom it may concern:

Be it known that I, GRAVES R. MAUPIN, a citizen of the United States, and a resident of Moberly, Missouri, have invented certain new and useful Improvements in Combination Boiler Tools, of which the following is a specification containing a full, clear, and exact description, reference being had to the accompanying drawings, forming a part hereof.

My invention relates to improvements in combination boiler tools and has for its primary object a tool which performs the two-fold function of first making a seat in the hand-hole of the water leg of a boiler and then seating the hand-hole cap therein.

A further object is to construct a combination boiler tool using rollers to form the seat of a hand hole and seat the cap with a mandrel having a removable expander tip so that the same tool may be used for both purposes without any change, except the tip.

In the drawings:

Figure 1 is a side elevation of my tool in position showing it forming the seat for the hand-hole cap.

Fig. 2 is a similar view showing the device employed in seating the cap.

Fig. 3 is a longitudinal section of the device showing the seating mandrel in position with parts thereof broken away and in section.

Fig. 4 is an enlarged side elevation of the cap seating tip made use of.

Fig. 5 is an end view of one of the tips showing the socket for receiving the end of the mandrel.

Fig. 6 is an end view of the mandrel showing the projection which fits into the socket.

Fig. 7 is a bottom plan view of the roll retainer.

Fig. 8 is a side elevation of the same.

Fig. 9 is an enlarged cross-sectional view of the mandrel and tip showing the manner of securing the same together, and also the means for preventing the locking pin from dropping out of the hole.

Fig. 10 is a cross-sectional view taken on the line 10—10 of Fig. 3.

Fig. 11 is a longitudinal sectional view of my device as applied to a power-driven tool.

Fig. 12 is a cross-sectional view on the line 12—12 of Fig. 11.

In the construction of my device I employ a cage 13. This cage is provided with openings 14 through which project tapered rollers 15. These tapered rollers are designed to come in contact with the edge of a hand-hole and besides making a smooth, burnished surface also taper it, as indicated by numeral 16. The cage 13 is provided at its rear end with a flange 17, against one face of which rests a boring ring 18, and against this ring 18 rests the collar 19. The collar 19 is loosely mounted on the cage and is provided with a circular recess 20. This recess is adapted to receive the ends of pins 21, which pins are inserted through openings 22 formed in the cage. The purpose of this groove or recess and pins is to prevent the collar from becoming detached. The collar has one of its flat faces recessed as at 23. This is to allow the collar to project slightly over the rolls 15. The front edge of the cage is provided with a curved surface 24 in which notches 25 are cut. The purpose of these notches is to hold the cage while the sleeve or stud 26 is being secured within the cage. This sleeve is provided with screw threads which are designed to co-act with the screw threads 27 formed in the cage. The cage is provided with an enlarged internal recess 28, which permits the insertion of the roll retainer 29. This roll retainer is provided with legs 30, the spaces between these legs being less than the diameter of the rolls to prevent the same from dropping into the cage when the mandrel and its tip have been removed. The roll retainer 29 is provided with an enlarged portion 31, which rests against a shoulder 32 formed in the cage, and is securely clamped between the shoulder 32 and the sleeve 26. After the sleeve has been secured in the cage,

the roll retainer 29 is provided with an enlarged portion 31, which rests against a shoulder 32 formed in the cage, and is securely clamped between the shoulder 32 and the sleeve 26. After the sleeve has been secured in the cage,

the lock nut 33 is screwed tight against the face 34 of the cage. This prevents the removal of the sleeve accidentally. The sleeve 26 is also provided with a longitudinal groove or grooves 35. The purpose of this is to lock the depth gage 36 in position on the sleeve. This is done by means of the set-screw 37 which is screwed through the depth gage and enters the slot, thus preventing the turning of the gage and, consequently, its movement on the sleeve. Over the sleeve 26 and to the rear of the gage 36 is secured a screw-threaded feeding sleeve 38. This sleeve is provided at its rear end with the opening 39, through which the mandrel 40 passes. The opening 39 is, however, smaller in diameter than the screw-threaded interior of the feeding sleeve, thus forming the shoulder 41 against which the collar 42 of the mandrel rests. The sleeve 26 is also provided with a pair of openings 43. These openings being to permit the insertion of a bar when securing the sleeve in the cage. The mandrel 40 is cylindrical in form and is provided on its rear end with a square projection 43^a, which is for the purpose of allowing a wrench to be used. Adjacent the portion 43^a are formed openings 44, which extend entirely through the mandrel and permit the insertion of a bar for operating the device. To the rear of the collar 42 is located a collar 45. This collar is secured to the mandrel by means of the tapered pin 46. This prevents any lateral movement of the mandrel within the feeding sleeve 38. The face of the collar 45, which abuts the feeding sleeve 38 is provided with a bore 47 in which is seated a spring actuated lug 48, and in the outer surface of the collar 45 is formed a slot 49. This slot allowing the handle 50, which is attached to the lug to be moved sideways and hold the lug in retarded or withdrawn position. Communicating with the slot 49 is a slot 51. This will permit the forward movement of the lug 48 when the handle 50 is brought into vertical position, and the forward pressure of the spring 52 will force the lug into the recess 53 cut in the feeding sleeve. This will cause the sleeve 38 to turn with the mandrel and force the mandrel forward. The opposite end of the mandrel 40 is provided with a square projection 54, and through this projection is a cylindrical bore 55. The square projection 54 is designed to enter the recess 56 of the mandrel tip 57. This mandrel tip is cylindrical for part of its length adjacent the recessed end, the balance being tapered as indicated by the numeral 58. Formed in the cylindrical portion of the mandrel tip 57 is a cylindrical opening 59. This cylindrical opening registering with the opening 55 is for the purpose of receiving the locking pin 60, by means of

which the mandrel and tip are secured together. In the cylindrical surface is also formed a groove 61, which is for the purpose of receiving a split spring ring 62, this ring preventing the accidental removal of the locking pin 50 when the mandrel is withdrawn.

It will be noted from Figs. 3 and 4 that the mandrel tips are slightly different in shape, the taper on the tip shown in Fig. 4 being longer than that shown in Fig. 3, the tip with the short taper being the tip for forming the seat while the tip shown in Fig. 4 is used for seating the cover.

Referring to Fig. 11 the screw-threaded recess 27 of the cage is provided with an undercut circular recess 63, the purpose of which is to receive a split ring 64. This split ring serves the twofold purpose of preventing the roll retainer from becoming dislodged as well as to prevent the collar retaining pins from dropping out. In this construction I employ a mandrel 65, which has its one end tapered so as to fit within the spindle or chuck of a drill press or similar tool. Adjacent this taper is a collar 66 which bears against the free end of a screw threaded sleeve 67. This screw-threaded sleeve is adapted to be secured in the head at a predetermined distance and then locked in position therein by means of a lock nut 68. In order to easily secure adjustment the end 69 of the sleeve is made preferably with a wrench engaging surface, and it is against this end of the sleeve that the collar 66 abuts, this limits the movement of the mandrel tip through the cage and consequently the size of the hole. Adjacent the collar 66 and formed integral with the mandrel 65 is a cylindrical projection 70 which terminates in a square projection 71, which is provided with a bore 72. This bore is designed to receive the pin 60 for locking the various mandrel tips desired to be used.

The operation of my device is as follows:

When it is desired to use the tool on new work, that is, where the hand-hole cap, as shown in Fig. 2, has not been used, the mandrel tip 57 is secured on the mandrel. This is done by removing the sleeve 38 from the sleeve 26. The tip 57 is then placed over the projection 54, the pin 60 inserted through the bores 59 and 55 and the spring ring 62 placed in position in the groove 61, the mandrel is then inserted through the sleeve 26, the depth gage 36 adjusted and secured in position and the mandrel rotated. Before rotating the mandrel, the sleeve 38 is screwed up sufficiently tight to bring the rolls 15 to bear against the edge of the hand-hole. The lug or dog 48 is then released and allowed to enter the recess 53, the mandrel is now rotated, this rotation turning also the sleeve 38, forcing the mandrel forward in the cage 130

and expanding the rollers. When sufficient amount of pressure has been brought to bear on the rollers, the lug 48 is withdrawn and the mandrel continued to revolve until it 5 again becomes loose in the hole, the dog is then again allowed to enter the recess 53 and the feeding forward continued until such time as the sleeve 38 comes in contact with the depth gage 36. This assures uniform sizes of all the hand-holes. The mandrel 40 and tip 57 together with sleeve 38 are now removed and the seating tip 73 secured on the mandrel. This tip, due to its longer taper, will allow the rollers to come 10 closer together. This is necessary so that the rollers may enter the interior of the hand-hole cap 74,—this is shown in Fig. 2. The device is then again rotated and fed forward until the cap is seated within the 15 hand-hole. This operation of seating the cap is, however, not an expanding operation, as the cap is previously tapped into the hole and this rolling only serves to make a tight metal-to-metal contact between the 20 cap and the hole by smoothing out any irregularities in the cap. The pressure set up on the inside of the water leg when the boiler is in operation is sufficient to hold the cap against dislodgment, but, at the same time, 25 the cap can be readily driven inward when it is desired to remove it for getting at the boiler tubes.

Having fully described my invention what I claim is:

- 35 1. A combination boiler tool comprising a cage, rollers mounted in said cage, a screw threaded sleeve secured in said cage, a mandrel having a detachable tip located in said sleeve, a depth gage adjustably carried by 40 said screw threaded sleeve, a feeder sleeve for feeding said mandrel forward and backward, and means carried by the mandrel and

adapted to engage with the feeder sleeve, whereby said mandrel and feeder sleeve are rotated simultaneously. 45

2. A combination boiler tool comprising a cage, expander rolls mounted in said cage, a screw-threaded sleeve secured in said cage, a lock-nut for locking said screw-threaded sleeve and cage together, a feeder sleeve 50 secured on the screw-threaded sleeve, a mandrel having a detachable tapered tip carried by said feeder sleeve, a collar revolubly secured on said cage, and means for rotating said feeder sleeve simultaneously with the 55 mandrel.

3. A combination boiler tool comprising a cage, expander rolls mounted in said cage, a screw-threaded sleeve secured in said cage, a lock-nut for locking said screw-threaded 60 sleeve and cage together, a feeder sleeve secured on the screw-threaded sleeve, a mandrel carried by said feeder sleeve, a tapered tip detachably secured to said mandrel, and a lug carried by the mandrel for revolving 65 the feeder sleeve simultaneously therewith.

4. A combination boiler tool comprising a cage, expansion rollers mounted in said cage, a roll retainer mounted in the cage, a screw-threaded sleeve mounted in the cage, a depth 70 gage carried by the screw-threaded sleeve, a feeder sleeve secured on the screw-threaded sleeve and adapted to contact with the depth gage, a mandrel secured in the feeder sleeve, a tapered tip detachably secured to the mandrel, means for securing said tip to the mandrel, and a spring-actuated lug carried by the mandrel, said lug adapted to cause the feeder sleeve and mandrel to revolve simultaneously and feed the mandrel forward or 75 backward.

In testimony whereof, I have signed my name to this specification.

GRAVES R. MAUPIN.
